CAP FOR SNAP FASTENERS

Otto J. Huelster, Waterbury, Conn., assignor to
 Scovill Manufacturing Company, Waterbury,
 Conn., a corporation of Connecticut

Application June 13, 1944, Serial No. 540,095

18 Claims. (Cl. 24—216)

1

This invention relates to snap fasteners of the type and kind employing sockets having yieldable portions for engagement with studlike elements in coupling and uncoupling an element with the socket. More particularly, the invention relates to the construction of the cap members of sockets of the kind under consideration, said cap members having means securing the socket part to a support and in positively retaining the socket member against shifting movement in the support. The novel features of the invention will be best understood from the following description when taken together with the accompanying drawing, in which certain embodiments of the invention are disclosed, and in which the separate parts are designated by suitable reference characters in each of the views; and in which:

Fig. 1 is a plan view of the cap side of the socket shown attached to a support.

Fig. 2 is a section on the line 2—2 of Fig. 1, on an enlarged scale; and

Fig. 3 is a side elevation of a cap shown detached and in the position assumed prior to attachment to the socket member of the socket part of the fastener.

In socket members of the type and kind under consideration, it has been desirable to produce a socket member relatively thin in its total thickness in order to present a minimum of bulk to facilitate passage through laundering machines of various kinds and classes, and furthermore to securely and firmly retain the socket member against displacement and shifting movement on the support to which it is attached.

The socket member herein disclosed includes structural features which accomplish the desired results in fasteners of this kind, and at the same time, produces a socket member of strong and durable construction which will withstand a reasonable amount of crushing strain without distortion to said member or interference with the proper functioning thereof.

In the accompanying drawing, the socket part of snap fasteners of the kind under consideration comprises a socket member 5 and a cap member 6, which might also be termed the attaching member for securing the member 5 to any suitable supporting sheet 7.

The member 5 comprises a ringlike body having an outwardly and downwardly curved wall portion 8 terminating at its lower end in an inwardly curved annular ringlike wall 9, preferably of curved or hook shaped cross sectional form, as clearly seen in Fig. 2 of the drawing. The upper

2

or inner end of the wall 8 terminates in a plurality of circumferentially spaced spring members 10 arranged within circumferential boundaries of the wall 8, and having at their lower ends inturned projections 11 adapted to engage a stud part of a fastener, not shown, in retaining such stud part against displacement from the socket part, as in other devices of this kind.

The wall 8 concludes in a short substantially straight portion 12 which parallels the perpendicular wall of the spring members 10, and this construction gives rigidity and reinforcement to the socket part in resisting crushing strains. Outwardly of the part 12 of the wall, and inwardly of the ring 9, is an annular passage 13 opening into the annular chamber 14 formed between the lower portion of the wall 8 and the ring 9. It will appear from a consideration of Fig. 2 of the drawing that the wall 8 and ring 9 are arranged in close proximity to each other, spaced apart sufficiently to receive the coupling prongs 15 of the member 6.

The member 6 comprises a central disc or domed portion 16, the periphery of which is offset, as seen at 17, where the domed portion joins circumferentially spaced and downwardly curved gripper flanges 18, the curvatures of which are substantially common to the curvatures of the domed portion 16, but offset with respect thereto, as at 17, and the peripheral edges of the gripper flanges 18 are concentric to the periphery of the disc or domed portion 16.

The prongs 15 are formed from that part of the material of the sheet from which the cap is formed, which would be occupied by the wide spacing, as at 19, between the flanges 18, as will clearly appear from a consideration of Fig. 3 of the drawing. However, the prongs 15 are of greater radial length than the corresponding length of the gripper flanges 18 in order to extend through the support 7 and pass into the opening 13, and finally into the chamber 14 of the socket member 5, the result of which operation is illustrated clearly at the right of Fig. 2 of the drawing.

In producing the cap part 6 as an article of manufacture, it will be made in accordance with the showing in Fig. 3, with prongs 15 arranged in a straight perpendicular line, and these prongs are so positioned with respect to the curved wall 8 of the member 5 as to pass downwardly over said wall and be guided into the chamber 14 in the manner stated and shown in the drawing.

Considering Fig. 1 of the drawing, it will be seen that the corners 20 of the gripper flanges

18 will be slightly rounded in order not to rupture the support 7 in firmly imbedding these flanges in the support in the operation of securing the members 5 and 6 thereto. In this operation the support will be slightly raised between adjacent ends of the gripper flanges or within the space 19, as indicated at 21 at the right of Fig. 2 of the drawing. These raised portions will aid in positively retaining the members 5 and 6 against shifting movement on the support, thus relieving strains on the prongs 15, which might tend to tear or rupture the support or have a cutting action therein.

In considering Fig. 2 of the drawing, it will appear that the diameter of the cap member 6 as defined by the peripheral edges of the gripper flanges is substantially the same as the diameter of the member 5, thus in the applied pressure of securing the members of the socket part to the support 7, the downward imbedded pressure of the gripper flanges 18 will be backed-up by the ring 9, which is flatly curved, to form in this respect a suitable backing plate which will not pierce or injure the support in any way. This flatness furthermore will minimize the total overall thickness of the complete socket part. It will also appear that the offsetting of the domed portion and gripper flanges as at 17 is such that the interior diameter of said offset portion 17 is slightly greater than the outer diameter of the wall 12. This construction provides for ample space between the domed portion 16 and the adjacent connecting annulus of the wall 12 and spring members 10 so as to preclude any severe binding of the supporting material therebetween, and assure that the entire impact of the gripping force on the interposed supporting material will be effected between the gripper flanges 18 and the ring 9. Further, the fact that the prongs 15 project axially out of and are integral with the offset portion 17 and with their perpendicular portions bent outwardly into the chamber 14 with the bent portions resting upon the wall 8, the prongs 15 serve as sort of pedestals to support the domed portion 16 a predetermined distance above the socket part 5 to protect the latter against any crushing strains.

One of the distinctive advantages of utilizing the circumferentially spaced gripper flanges on the cap member is to compensate for any unevenness that may prevail in the support to which the socket part is attached. In other words, each gripper flange will function as a gripping and securing element independently, and by reason of this fact, no distortion will be contributed to the socket part as a whole, and at the same time, a square mounting on the support is provided.

Having fully described my invention, what I claim as new and desire to secure by Letters Patent is:

1. In a snap fastener comprising socket and cap parts, a cap part comprising a central disc portion, a plurality of prongs extending integrally from the periphery of said disc portion at circumferentially spaced intervals, said prongs being arranged perpendicularly to the disc portion and substantially parallel to each other, a plurality of gripper flanges extending integrally from the periphery of the disc portion and arranged between said spaced prongs, and said gripper flanges extending outwardly and radially with respect to said disc and angularly with respect to said prongs.

2. In a snap fastener comprising socket and cap parts, a cap part comprising a central disc

portion, a plurality of prongs extending integrally from the periphery of said disc portion at circumferentially spaced intervals, said prongs being arranged perpendicularly to the disc portion and substantially parallel to each other, a plurality of gripper flanges extending integrally from the periphery of the disc portion and arranged between said spaced prongs, said gripper flanges extending outwardly and radially with respect to said disc and angularly with respect to said prongs, and said gripper flanges being offset with respect to the periphery of said disc.

3. In a snap fastener comprising socket and cap parts, a cap part comprising a central disc portion, a plurality of prongs extending integrally from the periphery of said disc portion at circumferentially spaced intervals, said prongs being arranged perpendicularly to the disc portion and substantially parallel to each other, a plurality of gripper flanges extending integrally from the periphery of the disc portion and arranged between said spaced prongs, said gripper flanges extending outwardly and radially with respect to said disc and angularly with respect to said prongs, said gripper flanges being offset with respect to the periphery of said disc, and said disc being domed outwardly in a direction opposite to the extension of the prongs with respect thereto.

4. In a snap fastener comprising socket and cap parts, a cap part comprising a central disc portion, a plurality of prongs extending integrally from the periphery of said disc portion at circumferentially spaced intervals, said prongs being arranged perpendicularly to the disc portion and substantially parallel to each other, a plurality of gripper flanges extending integrally from the periphery of the disc portion and arranged between said spaced prongs, said gripper flanges extending outwardly and radially with respect to said disc and angularly with respect to said prongs, said gripper flanges being offset with respect to the periphery of said disc, said disc being domed outwardly in a direction opposite to the extension of the prongs with respect thereto, said gripper flanges having a radial curvature substantially conforming with and offset with respect to the curvature in the dome of said disc, and peripheral edges of said gripper flanges being concentric with the periphery of said disc.

5. In a snap fastener comprising socket and cap parts, a cap part comprising a central disc portion, a plurality of prongs extending integrally from the periphery of said disc portion at circumferentially spaced intervals, said prongs being arranged perpendicularly to the disc portion and substantially parallel to each other, a plurality of gripper flanges extending integrally from the periphery of the disc portion and arranged between said spaced prongs, said gripper flanges extending outwardly and radially with respect to said disc and angularly with respect to said prongs, said gripper flanges being offset with respect to the periphery of said disc, said disc being domed outwardly in a direction opposite to the extension of the prongs with respect thereto, said gripper flanges having a radial curvature substantially conforming with and offset with respect to the curvature in the dome of said disc, peripheral edges of said gripper flanges being concentric with the periphery of said disc, and said gripper flanges having rounded outer corners.

6. A cap for a snap fastener, said cap comprising an imperforated center portion terminating in an offset marginal edge, a plurality of cir-

cumferential gripper flanges extending integrally from the offset marginal edge of said center portion and radially with respect to said portion, said gripper flanges being widely spaced and terminating in outer curved edges, and means extending integrally from the marginal edge of said center portion intermediate said gripper flanges for securing the cap to a support.

7. A cap for a snap fastener, said cap comprising an imperforated center portion terminating in an offset marginal edge, a plurality of circumferential gripper flanges extending integrally from the offset marginal edge of said center portion and radially with respect to said portion, said gripper flanges being widely spaced and terminating in outer curved edges, means extending integrally from the marginal edge of said center portion intermediate said gripper flanges for securing the cap to a support, said last named means comprising substantially V-shaped prongs extending perpendicularly to the center portion in alignment with said offset marginal edge.

8. A cap for securing snap fastener parts to a support, said cap comprising a center portion terminating in a marginal edge, a plurality of cap securing members extending integrally from said edge and angularly to said center portion, and means integral with said edge of the center portion forming intermediate said members circumferentially spaced and totally independently functioning grippers cooperating with said members in securing the cap to a support.

9. A cap for securing snap fastener parts to a support, said cap comprising a center portion terminating in a marginal edge, a plurality of cap securing members extending integrally from said edge and angularly to said center portion, means integral with said edge of the center portion forming intermediate said members circumferentially spaced and totally independently functioning grippers cooperating with said members in securing the cap to a support, said grippers being offset with respect to the center portion, and said grippers terminating in curved ends.

10. A cap for securing snap fastener parts to a support, said cap comprising a center portion terminating in a marginal edge, a plurality of cap securing members extending integrally from said edge and angularly to said center portion, means integral with said edge of the center portion forming intermediate said members circumferentially spaced and totally independently functioning grippers cooperating with said members in securing the cap to a support, said grippers being offset with respect to the center portion, said grippers terminating in curved ends, and the curved ends of said grippers being of greater circumferential length than the ends thereof joining the edge of the center portion.

11. A snap fastener socket member comprising a socket part and a cap part, the socket part comprising a ring body having an inturned marginal portion of curved hook shaped cross sectional contour, the ring body being partially defined by a curved annular wall, said cap part comprising a central domed portion terminating in an offset marginal edge, a plurality of circumferential gripper flanges extending integrally from said marginal edge and radially with respect to said center portion, said gripper flanges being arranged over and cooperating with the marginal portion of the socket part in supporting said parts on a support disposed therebetween, the marginal edge of the cap part in-

cluding intermediate the gripper flanges circumferentially spaced prongs adapted to pass through the support and to engage the curved annular wall of the socket part in securing said parts together and in maintaining the domed portion of the cap part in predetermined relationship with respect to said socket part, and the inside diameter of said domed portion being greater than the outside diameter of the annular wall of the socket part arranged within the prongs adjacent said domed portion.

12. A snap fastener socket member comprising a socket part and a cap part, the socket part comprising a ringlike body having an inturned marginal portion of curved hook shaped cross sectional form presenting a curved ringlike upper surface on said socket part, a plurality of yieldable members spaced circumferentially of and extending downwardly from the other end of said body, the free lower ends of said members having inturned stud engaging portions arranged within the circumferential boundaries of said body, said cap part comprising a central domed portion, a plurality of outwardly and radially extending circumferentially spaced flanges at the periphery of the domed portion and offset with respect thereto, said flanges being widely spaced at adjacent edges thereof, said domed portion including prongs arranged at the periphery thereof intermediate said flanges and engaging the inturned flanges of the socket part in securing said parts to a support arranged between said parts, and said flanges overlying the upper surface of said marginal portion and curved to substantially conform therewith in firmly gripping the support therebetween.

13. A snap fastener socket member comprising a socket part and a cap part, the socket part comprising a ringlike body having an inturned marginal portion of curved hook shaped cross sectional form presenting a curved ringlike upper surface on said socket part, a plurality of yieldable members spaced circumferentially of and extending downwardly from the other end of said body, the free lower ends of said members having inturned stud engaging portions arranged within the circumferential boundaries of said body, said cap part comprising a central domed portion, a plurality of outwardly and radially extending circumferentially spaced flanges at the periphery of the domed portion and offset with respect thereto, said flanges being widely spaced at adjacent edges thereof, said domed portion including prongs arranged at the periphery thereof intermediate said flanges and engaging the inturned flanges of the socket part in securing said parts to a support arranged between said parts, said flanges overlying the upper surface of said marginal portion and curved to substantially conform therewith in firmly gripping the support therebetween, and the outside diameter defined by the flanges of the cap part being substantially the same as the outside diameter defined by the marginal portion of the socket part.

14. A snap fastener socket member comprising a socket part and a cap part, the socket part comprising a ringlike body having an inturned marginal portion of curved hook shaped cross sectional form presenting a curved ringlike upper surface on said socket part, a plurality of yieldable members spaced circumferentially of and extending downwardly from the other end of said body, the free lower ends of said members having inturned stud engaging portions arranged within the circumferential boundaries of said body, said

cap part comprising a central domed portion, a plurality of outwardly and radially extending circumferentially spaced flanges at the periphery of the domed portion and offset with respect thereto, said flanges being widely spaced at adjacent edges thereof, said domed portion including prongs arranged at the periphery thereof intermediate said flanges and engaging the inturned flanges of the socket part in securing said parts to a support arranged between said parts, said flanges overlying the upper surface of said marginal portion and curved to substantially conform therewith in firmly gripping the support therebetween, said flanges forming independent grippers engaging the support, and the support extending outwardly in the spaces between said flanges in keying the cap and socket against shifting movement on the support.

15. In a snap fastener comprising socket and cap parts, the socket part comprising a ringlike body having a reversely curved annular marginal portion, said marginal portion presenting a curved ringlike upper surface on said socket part, a cap part comprising a central disc-like portion, a plurality of prongs spaced circumferentially of the peripheral edge of said disc portion, a plurality of circumferentially elongated and spaced gripper flanges at the periphery of said disc portion and intermediate said prongs, said prongs engaging the marginal portion of the socket part in securing said parts together and to a support arranged therebetween, and said gripper flanges being curved and arranged over the curved surface of the marginal portion in firmly gripping a support therebetween.

16. The combination with a snap fastener member adapted to be secured to one surface of a support and having an annular marginal portion, of another member for securing the first named member to said support, said second member being arranged on the other surface of the support and having circumferentially spaced prongs extending through the support and engaging the marginal portion of the first named member in securing the members to said support, said

second named member having circumferentially spaced independent grippers, and said grippers and marginal portion having aligned curved surfaces between which the support is firmly gripped in securing said members to the support.

17. The combination with a snap fastener member adapted to be secured to one surface of a support and having an annular marginal portion, of another member for securing the first named member to said support, said second member being arranged on the other surface of the support and having circumferentially spaced prongs extending through the support and engaging the marginal portion of the first named member in securing the members to said support, said second named member having circumferentially spaced independent grippers, said grippers and marginal portion having aligned curved surfaces between which the support is firmly gripped in securing said members to the support, and said second named member having an offset central domed portion offset outwardly with respect to the second named surface of the support.

18. The combination with a snap fastener member adapted to be secured to one surface of a support and having an annular marginal portion, of another member for securing the first named member to said support, said second member being arranged on the other surface of the support and having circumferentially spaced prongs extending through the support and engaging the marginal portion of the first named member in securing the members to said support, said second named member having circumferentially spaced independent grippers, said grippers and marginal portion having aligned curved surfaces between which the support is firmly gripped in securing said members to the support, said second named member having an offset central domed portion offset outwardly with respect to the second named surface of the support, and end portions of said grippers circumferentially enveloping part of said first named member when said members are attached to a support.

OTTO J. HUELSTER.
